WASHING MACHINE

Herbert F. Bariffi, Hamden, Conn., assignor to
General Electric Company, a corporation of
New York

Application September 21, 1940, Serial No. 357,744

6 Claims. (Cl. 68—23)

The present invention relates to washing machines of the type in which clothes are washed and centrifugally dried in a single tube or receptacle.

It has heretofore been suggested that the clothes be rinsed by spraying fresh water into the tub during centrifugal drying, this being known as "spray rinsing."

The object of my invention is to provide an improved construction and arrangement for spray rinsing the clothes during centrifugal drying, and for a consideration of what I believe novel and my invention, attention is directed to the following description and the claims appended thereto.

In the accompanying drawing, Fig. 1 is a sectional elevation of a washing machine embodying my invention; Fig. 2 is a perspective view of the driving mechanism for the washing machine; and Fig. 3 is a control diagram.

Referring to the drawing, there is shown a washing machine having an outer casing or tank 1 in the upper part of which is a tub or clothes receptacle 2 having a bladed agitator 3 therein. In the upper part of the tub side walls are openings 4 which define the liquid level in the tub during washing and through which liquid is centrifugally discharged during drying. By a suitable arrangement, for example that shown in Patent 2,161,618—G. W. Dunham, the agitator is selectively oscillated for washing or the receptacle is rotated for centrifugal drying by a vertical shaft 5 extending up through a sleeve 6 fixed to the bottom wall of the outer casing.

The machine is driven by a two-speed electric motor having an armature 1 and a high speed winding 8 and a low speed winding 9. Fixed to the motor shaft 10 is a pulley 11 which drives a shaft 12 through a belt 13 and a pulley 14 fixed to the shaft 12. Integral with the shaft 12 is a worm 15 which meshes with a worm gear 16 having a socket 17 for receiving the crank pin of a rack 18. The rack reciprocates in a guide 19 pivotally carried on arms 20 fixed to a rock shaft 21. By turning the rock shaft in a counter-clockwise direction, as viewed in Fig. 2, the rack is moved into engagement with a pinion 22 fixed to the shaft 5. Also fixed to the rock shaft 21 is an arm 23 having its free end loosely received in a groove 24 in a clutch member 25 splined to the shaft 12. When the rock shaft 21 is moved in a clockwise direction, as viewed in Fig. 2, the clutch member 25 is moved axially along shaft 12 to a position in which its teeth 26 engage re-

cesses 27 in a spiral gear 28 which is loose on the shaft 12 and which meshes with a spiral gear 29 keyed to the shaft 5. When the rock shaft 21 is in the position illustrated, the clutch member 25 is out of engagement with the gear 28 and the rack 18 is out of engagement with the pinion 22 so that the shaft 5 is stationary. The rock shaft 21 is turned by a control knob 30 fixed to a shaft 31 slidably and rotatably carried in walls 32, 33, and 34 of a control box 35. Fixed to the shaft 31 is a pin 36 which fits in an elongated slot 37 in the hub of a bevel gear 38. The bevel gear 38 accordingly turns with the knob 30. The rotation of the bevel gear 38 is transmitted to the rock shaft 21 through bevel gears 39, 40, 41, 42, and 43. The control knob 30 is shown in the "off" position. When the control knob is turned to the position in which the pointer 44 points to "dry" the rock shaft 21 is moved to the position 20 in which the clutch member 25 engages the gear 28 and the shaft 5 is rotated at its centrifugal extracting speed through the gears 28 and 29. When the knob is turned to the position in which the pointer 44 points to "wash," the rack 18 is moved into engagement with the pinion 22 and the shaft 5 is oscillated at the washing speed.

During washing an excess of liquid is placed in the receptacle 2 so that some of the liquid overflows through the openings 4 and is conducted from an opening 45 in the bottom of the outer casing through a conduit 46 and valve 47 to the inlet of a pump 48. The discharge of the pump is connected by a flexible hose 49 to a discharge nozzle 50 which during washing is inserted through an opening 51 in the cover 52 for the outer casing so as to discharge onto an annular filter 53 carried on the upper rim of the receptacle 2. When the outer casing is to be emptied, the discharge nozzle may be arranged to discharge to a drain. The pump is driven by a pulley 54 fixed to the pump shaft 55 by a belt 56 and a pulley 57 integral with the pulley 14. Since the pump is driven directly from the motor it rotates throughout the washing and drying operations. During washing the liquid which overflows through the openings 4 is pumped from the bottom of the outer casing onto the filter 53.

During centrifugal drying the liquid in the clothes is centrifugally discharged through the openings 4 against the side walls of the outer casing, whence it falls into an annular trough 58 fixed to the outer casing below the receptacle 2. The liquid caught in the trough 58 drains

through a conduit 59 to a solenoid-operated valve 60, shown in detail in Fig. 3, which either conducts the liquid through a conduit 61 to the bottom of the outer casing or conducts the liquid through a conduit 62 to a drain.

The tub is filled through a conduit 63 connected to the water supply and having a discharge nozzle 64 directed into the receptacle 2. The conduit 63 is controlled by a valve 65 which is opened only when the machine is to be filled. Around the valve 65 is a by-pass conduit 66 controlled by a solenoid-operated valve 67, shown in detail in Fig. 3. The valve 67 is opened only when fresh water is to be introduced into the receptacle during centrifugal drying to rinse the clothes at which time the valve 65 is closed.

During the washing and drying operations the driving motor is energized through the circuit extending from a conductor 68 connected to one side of the power line, a line switch 69, conductor 70, spring contact arm 71, and contact 72 connected to one end of the high speed winding 8. The other end of the high speed winding 8 is connected through conductor 72' to the motor armature 7 which is connected through a conductor 73 to the grounded side of the power line. The spring arm 71 is normally biased into engagement with the contact 72. When the control knob 30 is in the "dry" position a key 14 on the shaft 31 is in register with a keyway 75 in the wall 33 of the control box 35. The knob 30 can accordingly be pulled outward away from the control box so a cam 76 on the shaft 31 engages a projection 77 on the spring contact arm 71 and moves the contact arm away from the contact 72 and into engagement with a contact 78 connected to one end of the low speed motor winding 9. This shifts the motor from the high speed to the low speed position. The closing of the circuit to the contact 78 closes a circuit to a solenoid 79, operating the valve 60. The valve 60 is biased by a spring 80 to a position in which the liquid flowing through the valve is conducted through the conduit 61 to the bottom of the outer casing. Upon energizing of the solenoid 79, the valve plunger is moved to the left, as viewed in Fig. 3, shutting the passage to the conduit 61 and opening the passage to the conduit 62, so that the liquid flowing through the valve is conducted to the drain. The closing of the circuit through the contact 78 also closes a circuit to a solenoid 81 in the valve 67 extending from the contact 78 which is connected to the line conductor 68, through conductor 82, solenoid 81, conductor 83, centrifugal switch 84, and conductor 85 to the ground side of the power line. The centrifugal switch 84 is mounted on the motor shaft 10 and is arranged so that the switch is open during the high speed operation of the motor and is closed when the motor speed is low enough so that the clothes will not be damaged by impact with the fresh water discharged through the nozzle 64. The solenoid 81 can be energized only when the motor is connected in its low speed position and when the motor speed has been reduced sufficiently to close the centrifugal switch 84. This is in effect an interlock between the valve controlling the rinse water and the switch controlling the motor speed. Upon energizing of the solenoid 81 the valve 67 is opened to admit fresh water into the receptacle 2 through the nozzle 64. This water is thrown outwardly through the clothes by centrifugal force, rinsing the same. When the control knob 30 is pushed inward the spring contact arm moves away from the contact 75

78 into engagement with the contact 72. This opens the circuits to the solenoids 79 and 81, causing the return of the valves 60 and 67 to the positions illustrated.

5 In the use of the machine the receptacle 2 is filled until water overflows through the openings 4 by opening the valve 65 so that fresh water is admitted from the water supply 63 through the nozzle 64. The switch 69 is then closed to start the motor, the valve 47 in the pump inlet is opened, the clothes and washing compound are put in the receptacle, and the control knob 30 is turned to the "wash" position. The rack 18 is now in engagement with the pinion 22 and the agitator 3 is oscillated by the shaft 5. The pump 48 pumps water from the bottom of the outer casing 1 through the flexible hose 49 and nozzle 50 onto the filter 53. Since the water is continually overflowing through the openings 4 the water in the clothes receptacle is continuously filtered throughout the washing operation. At the conclusion of the washing operation the valve 47 in the pump inlet 46 is closed and the control knob is turned to the "dry" position, 20 moving the rack 18 out of engagement with the pinion 22 and moving the clutch member 25 into engagement with the spiral gear 28. This completes a driving connection from the motor to the receptacle 2 through the spiral gears 28 and 29 and the vertical shaft 5. The clothes receptacle 30 is now rotated at high speed to centrifugally dry the clothes. The liquid in the clothes is discharged through the openings 4 against the side walls of the outer casing and falls into the annular trough 58, whence it drains through the conduit 59, valve 60, and conduit 61 to the bottom of the outer casing. When the drying operation is completed the control knob 30 is pulled outward so the spring contact arm 71 is moved by the cam 76 into engagement with the contact 78 connected to the low speed motor winding 9. This closes a circuit through the solenoid 79 of the valve 60, closing the passage to the conduit 61 and opening the passage to the conduit 62 so that the liquid caught in the trough 58 will be conducted to the drain. As soon as the motor speed is reduced to a safe value the centrifugal switch 84 closes and thereby completes a circuit to the solenoid 81 of the valve 67. This opens the valve 67 and causes the introduction of fresh water from the water supply 63 through the conduit 66 and nozzle 64. With this arrangement it is impossible to introduce rinsing water into the clothes receptacle when the speed of rotation is high enough so that the fabric can be damaged by the impact of the rinsing water. When the rinsing operation is completed the control knob 30 is pushed inward, opening the circuit to the solenoid 81 and thereby cutting off the flow of rinsing water. At the same time the circuit to the solenoid 79 is opened and the valve 60 is returned to the position illustrated in which the passage to the conduit 62 is closed and the passage to the conduit 61 is opened. The liquid remaining in the clothes at the end of the rinsing operation will be centrifugally discharged through the openings 4 and caught in the trough 58 and returned to the outer casing through the conduit 61. The rotation of the receptacle is stopped by turning the control knob 30 to the "off" position. After the clothes have been removed, the valve 47 is opened and the liquid in the bottom of the outer casing is pumped through the flexible hose 49 which may be arranged to fill the receptacle 2 for washing another batch of clothes 55

or may be arranged to discharge to a drain and thereby empty the outer casing.

What I claim as new and desire to secure by Letters Patent of the United States is:

1. In a washing machine, a clothes receptacle, means for selectively rotating the receptacle at high and low speeds for centrifugal drying, provisions for introducing rinsing liquid to the receptacle, and a speed responsive device for preventing the introduction of rinsing liquid during the high speed rotation of the receptacle.

2. In a washing machine, a receptacle for receiving liquid and clothes to be washed and centrifugally dried, mechanism for selectively agitating the liquid and clothes in the receptacle for washing and for rotating the receptacle at high and low speeds for centrifugal drying, provisions for introducing rinsing liquid into the receptacle, a control for said mechanism movable to washing and drying positions and effective while in the drying position to control the introduction of rinsing liquid, and interlock means for preventing the introduction of rinsing liquid during high speed rotation of the receptacle.

3. In a washing machine, a receptacle for receiving liquid and clothes to be washed and centrifugally dried, mechanism for selectively agitating the liquid and clothes in the receptacle for washing and for rotating the receptacle at high and low speeds, provisions for introducing rinsing liquid into the receptacle, a device responsive to the speed of the receptacle, and a valve controlled by said speed responsive device for limiting the introduction of rinsing liquid to the low speed rotation of the receptacle.

4. In a method of spray rinsing and centrifu-

gally drying the clothes, the steps of centrifuging the clothes in a centrifuge receptacle at a speed above that at which the clothes may be sprayed with liquid without injury to the fabric by impact of the liquid spray and spraying the clothes with rinsing liquid while centrifuging at a lower speed at which the impact of the liquid will not injure the fabric, said lower speed being such that the clothes are held by centrifugal force against the side walls of the receptacle.

5. In a washing machine, a clothes receptacle, means for rotating the receptacle to centrifugally dry the clothes at a speed at which the impact of a liquid spray on the clothes would injure the fabric, means for spray rinsing the clothes, means for reducing speed of the receptacle, and a control for the rotation of the receptacle and the spray rinsing movable first to the high speed position and second to a position controlling the spraying of rinsing liquid and the reduction of the receptacle speed to a value insufficient to cause injury to the fabric.

6. In a washing machine, a clothes receptacle, means for rotating the receptacle to centrifugally dry the clothes at a speed at which the impact of a liquid spray on the clothes would injure the fabric, means for spraying the clothes during the centrifugal drying operation with rinsing liquid, a control movable to positions controlling the rotation of the receptacle and the rinsing, and means responsive to movement of the control to the rinsing position for reducing the speed of the receptacle whereby the impact of the spray on the clothes is reduced to a value insufficient to cause injury to the fabric.

HERBERT F. BARIFFI.
